WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TUBE FRAME FOR AXMINSTER LOOMS

Application filed February 19, 1929. Serial No. 341,118.

This invention relates to improvements in tube frames for Axminster looms and it is the general object of the invention to provide an improved means for retaining a chain engaging 5 spring hook or latch so that the same may be readily removed when repair is needed but will ordinarily be held securely in position.

The usual Axminster loom employs a pair of transporting chains between which are suspended tube frames carrying the variously colored tuft yarns which form the surface of the Axminster fabric. The tube frames are held by releasable connections to the chain and these connections are engaged by 10 clutches so that the tube frames one at a time may be moved from the chain to tuft forming position near the fabric. It is desirable that the connection between the tube frame and the chains be durable and also quickly 15 replaceable in case of breakage. It has been customary heretofore to employ in tube frames both of the narrow and wide type a pair of spring members held to the brackets on the ends of the tube frames by means of 20 screws. I find that after the springs have been replaced several times the screws are not strong enough to be held very tightly to the bracket and it is an object of my present invention to eliminate the use of screws or 25 similar connections between the springs and the bracket, this result being accomplished 30 preferably by relying upon the inherent resilience of the spring or springs to hold a retaining pin in position.

In the usual Axminster loom there is a stop motion which operates to stop the loom if the tube frame fails to be released from the transporting chains. This motion usually cooperates with a projecting portion of 35 the tube frame. It is a further object of my present invention to provide the latch springs with a lower bent portion which extends around a retaining pin to hold the latter in position, the lower portion of the spring projecting outwardly from the tube frame to

place under strain that portion of the spring which engages the retaining pin, said projecting portion cooperating with the stop motion and also being engageable by an appropriately formed tool to be pressed inwardly with respect to the tube frame so as to release the retaining pin.

It is a more particular object of my invention to provide a tube frame with a bracket having an opening therein through which 55 may extend a deformed part of a spring latch, said deformed part cooperating with a retaining pin in such a way as to prevent endwise movement of the latter, thereby holding 60 said pin in fixed position with respect to the tube frame and bracket. It is sufficient for the purposes of my present invention if the retaining pin, spring and bracket are so related that it is necessary to move a portion 65 of the spring relatively to the bracket in order to provide clearance for the removal of the pin. This result may be accomplished in the different way set forth hereinafter but I do not wish to be limited to these particular 70 forms of pins or engaging portions therefor.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a front elevation of one end of a tube frame formed according to my invention, the preferred form of the invention being shown, parts being in section and there being shown also in vertical section the cooperating clutch,

Fig. 2 is an end elevation looking in the direction of arrow 2, Fig. 1,

Fig. 3 is an enlarged detailed horizontal section on line 3—3 of Fig. 1,

Fig. 4 is a view similar to a portion of Fig. 90

1 but with a modified form of retaining pin, and

Fig. 5 is a detailed horizontal section on line 5—5 of Fig. 4.

5 Referring particularly to Fig. 1, I have shown a tube frame 10 which may be of tubular metallic stock formed substantially rectangular in cross section. A bracket or head 11 has a spool bearing portion 12 to receive the gudgeon of a spool S and said bracket may also be provided with a chain engaging member 13 having an offset tongue 14 to extend between the links 15 of a transporting chain. The members 11 and 13 are provided 10 with parallel spaced arms 16 and 17, respectively, which are inserted into the tubular bar 10 and held in position by screws 18.

A clutch C is mounted on a stud 19 which is supported by and movable with a trans- 20 ferrer arm not shown. Said clutch is movable angularly about the axis of the stud when the tube frame is adjacent the cloth to effect proper entry of the tuft yarns between the warp threads of the fabric. The upper 25 portion of the clutch is provided with a releasing screw 20 which engages a portion of the spring latch 21. A plunger having a head 22 is also slidably mounted in the clutch and is part of the previously mentioned loom 30 stopping mechanism. The upper end of the spring latch 21 is formed with a hook 23 as shown in Fig. 1 to lie over and have tube frame supporting engagement with one of the links 15 of the transporting chain.

35 The matter thus far described is of common construction and of itself forms no part of my present invention. It is to be understood that the transporting chain is given successive movements so that the tube frames, 40 several of which are employed in the loom, will be presented successively to tuft forming position. The movement of the chain is intermittent and while it is at rest the clutches will move inwardly to engage the spring hook 45 to move the latter to the dotted line position shown in Fig. 1, after which the clutch is moved downwardly, the tube frame moving with the clutch because of the fact that the hook 23 is out of holding position with respect to the transporting chain.

50 My invention relates more particularly to the manner for retaining the spring latch in position on the tube frame. As shown in Figs. 1, 2 and 3 I have provided the member 55 13 with a vertical slot 30. The lower end of the spring is formed with a V-shaped bend 31 having the vertex thereof extending into the tube frame. The lower portion of the spring normally projects as at 32 to the right 60 of the member 13 as shown in Fig. 1. The preferred form of the pin as shown in Figs. 1, 2 and 3 is indicated at 40 and is shown more 65 particularly in Fig. 3, where it will be noted that the intermediate portion of said pin 41 is reduced, thus defining heads 42 at the ends

of the pin. The vertex of the V-shaped bend in the spring is received between the heads and the two sides of the bend are normally under strain or stressed so as to hold said pin against the upright portion of the member 13. In this way the pin is held against longitudinal displacement by reason of the fact that the spring is restrained against transverse movement with respect to the tube frame by the walls of the slot 30.

70 The slot is sufficiently large to permit unobstructed insertion of the V-shaped portion of the spring, but after said portion and the pin are placed as shown in Fig. 1 they will be held substantially rigid with respect to the 80 tube frame.

In the modified form of pin shown in Figs. 4 and 5 I provide a pin 50 with an offset portion 51 proportioned to enter the slot 30. The inner portion of the pin as shown at the left 85 hand side thereof in Fig. 5 has a recess 52 to receive the spring, the pin in effect being formed by a single punching and cutting-off operation. In the modified form it will be seen that the pin is held against longitudinal 90 movement by engagement with the sides of the slot 30 and also by reason of the fact that the spring which enters the slot 52 is held substantially in position by the side walls of the slot 30.

95 In operation that portion of the spring which lies within the tube frame either is substantially rigid, the pin serving to retain the spring in position and being held as shown in Fig. 1 by the resilience of the V-shaped portion 100 of the spring. When it is desired to replace a spring an appropriate tool T, as shown in dot and dash lines in Fig. 4, may be moved against the projecting end 32 of the spring to move said end inwardly toward the tube 105 frame. This action will result in a deformation of the V-shaped portion 31 until the same assumes some such a form as indicated in dotted lines in Fig. 4, after which the pin may be moved endwise to pass out of one or another of the notches 53 formed in the opposite vertical walls of the tube frame 10 as shown clearly in Fig. 1.

110 After a new spring is inserted and held deformed as indicated in Fig. 4 the same pin or a fresh pin may be put in position, after which the tool T may be removed and the resilience of the spring will move the pin against the bracket due to the fact that the portions of the spring which engage the upper and lower ends of the slot are inclined.

115 With respect to the modified form of the invention, particularly as shown in Fig. 5, it will be seen that the amount by which the V-shaped portion of the spring must be 120 moved into the tube frame before the pin of the modified form can be removed is substantially twice the offset, due to the fact that said offset enters the recess 52 on the side of the pin opposite the slot 30. For this reason 125 130 135

the modified form of pin is subject to less accidental displacement than is the case with the preferred form of pin.

From the foregoing it will be seen that I have provided a very simple form of attaching means for a tube frame spring latch, said means including a pin which is held in position by the resilience of the spring. It will further be seen that the portion of the 10 spring which enters the tube frame has at least one side thereof inclined so as to cooperate with the slot in the bracket to hold the pin against said bracket. Also, the 15 spring latch may be removed or replaced without disturbing the bracket 11. It will also be seen more specifically that the pin and spring have interengaging portions which prevent longitudinal displacement of the pin due to the fact that the spring is held 20 against displacement by the slot 30.

Having thus described my invention it will be seen that changes and modifications may be made therein by those skilled in the art without departing from the spirit and scope 25 of the invention and I do not wish to be limited to the details herein disclosed, but what I claim is:

1. In an Axminster tube frame having a longitudinal bar, a bracket secured to the bar 30 and having an opening therethrough, an inherently resilient spring latch extending through the opening and engaging the bracket on opposite sides of the opening, and latch retaining means held against the bracket by 35 the resilience of that portion of the spring latch which passes through the opening.

2. In an Axminster tube frame having a longitudinal bar, a bracket secured to the bar 40 and having an opening therethrough, an inherently resilient spring latch having a portion thereof bent to have inclined sides which extend through the opening and engage the bracket on opposite sides of the opening, and a retaining member interposed between the 45 inclined sides and the bracket and held against the latter by the resilience of said inclined sides.

3. In an Axminster tube frame having a longitudinal bar, a bracket secured to the bar 50 and having an opening therethrough, an inherently resilient spring latch entering the opening at one side thereof and being bent to leave the opening at the opposite side thereof, said spring latch engaging the bracket on opposite sides of the opening, and a retaining member located between a bracket 55 and the bent portion of the spring latch and held by the resilience of the latter against the bracket.

60 4. In an Axminster tube frame having a longitudinal bar, a bracket secured to the bar and having an opening therethrough, an inherently resilient spring latch having a portion formed with a surface inclined with respect to the bracket, said portion with the in-

clined surface extending through the opening, and a latch retainer held against the bracket by the resilience of that portion of the latch which passes through the opening.

5. In an Axminster tube frame having a longitudinal bar, a bracket secured to the bar and having an opening therethrough, an inherently resilient spring latch the lower portion of which passes through the slot and engages that portion of the bracket adjacent the upper end of the slot, the portion of the spring latch which enters the slot being bent and extending out of the slot and in contact with that portion of the bracket adjacent the lower end of the slot, and retaining means interposed between the bent portion of the spring latch and that side of the bracket opposite the side of the slot which the spring latch enters, the inherent resilience of the spring latch holding the device against the bracket.

6. In an Axminster tube frame having a longitudinal bar, a bracket secured to the bar and having an opening therethrough, a spring latch the lower end of which is inherently resilient and extends into the opening, a retaining pin held by the inherent resilience of the lower end of said latch in engagement with that portion of the bracket opposite the side where the latch enters the opening, and a shoulder formed on said pin to engage the latch and be prevented by the latter from moving longitudinally.

7. In a tube frame for an Axminster loom, a longitudinal bar, a bracket member secured to the bar having an opening therethrough, the latch member having a resilient portion which extends through the opening, and a retaining element held by the resilience of the latch member against the bracket member, said retaining element having a shoulder to engage one of the members and being held thereby against longitudinal movement.

8. In an Axminster tube frame, a bar, a bracket secured to the bar and having an opening therethrough, a latch the lower end of which is resilient and extends into the opening to engage the bracket on one side of said opening and is bent and extends out of the opening to engage the bracket on the opposite side of the opening, the latter portion projecting beyond the outer surface of the bracket to be in position to be engaged and moved toward the bracket to cause deformation of that portion of the latch which extends through the opening, and a retaining element engaged and held against the bracket by the inherently resilient portion of the latch which extends through the opening.

9. In an Axminster tube frame, a bar, a bracket secured to the bar and having an opening therethrough, a latch the lower end of which is resilient and extends through and is substantially as wide as the slot, the resilient portion of the latch engaging that

part of the bracket adjacent the upper end of the slot and extending through the latter and being bent to project out of the slot on the same side of the bracket as the side from which the latch enters the slot, the portions of the brackets defining the sides of the slots acting to prevent substantial sidewise movement of the latch, and a pin held against the bracket by the inherent resilience of the bent portion of the latch which extends through the slot.

10. In an Axminster tube frame, a bar, a bracket secured to the bar and having an opening therethrough, a latch the lower end of which is resilient and extends through and is substantially as wide as the slot, the resilient portion of the latch engaging that part of the bracket adjacent the upper end of the slot and extending through the latter and being bent to project out of the slot on the same side of the bracket as the side from which the latch enters the slot, the portions of the brackets defining the sides of the slots acting to prevent substantial sidewise movement of the latch, and a pin held against the bracket by the inherent resilience of the bent portion of the latch which extends through the slot, the pin having a shoulder to be engaged by the latch whereby longitudinal movement of the pin is resisted.

11. In an Axminster tube frame, a longitudinal bar, a bracket member secured to the bar and having an opening therethrough, a latch member the lower portion of which is resilient and extends from the outer side of the bracket through the opening and is bent and then returns through the opening to project beyond the outer side of the bracket, the latch member being substantially the same width as the width of the slot, and a retaining element having a shoulder to engage one of the members to be held by the latter against longitudinal movement.

12. In an Axminster tube frame, a longitudinal bar, a bracket member secured to the bar and having an opening therethrough, a latch member the lower portion of which is resilient and extends from the outer side of the bracket through the opening and is bent and then returns through the opening to project beyond the outer side of the bracket, the latch member being substantially the same width as the width of the slot, and a retaining element having a shoulder to engage the latch member to be held by the latter against longitudinal movement, said latch member acting by the inherent resilience thereof to hold the pin against the bracket.

13. In an Axminster tube frame, a bar, a bracket secured to the bar and having an opening therethrough, a latch member the lower portion of which is resilient and extends into the opening in the bracket and is bent to project back through the opening, the lower portion of the latch having engage-

ment with the bracket at the top and bottom of the slot, and a pin having an offset intermediate portion which projects into the slot of the bracket on one side and on the other side has a recess to cooperate with the latch member, said portion of the latch which extends into the recess, acting by its inherent resilience to hold the said offset pin against the bracket, and against longitudinal movement.

In testimony whereof I have hereunto affixed my signature.

WILLIAM W. ROBERTSON.
